UNITED STATES PATENT OFFICE.

ERNEST KOELLA, OF KNOXVILLE, TENNESSEE.

SEWING-MACHINE.

1,143,286.

Specification of Letters Patent. Patented June 15, 1915.

Application filed December 22, 1911, Serial No. 667,312. Renewed April 16, 1915. Serial No. 21,849.

To all whom it may concern:

Be it known that I, ERNEST KOELLA, a citizen of the United States, residing at Knoxville, in the county of Knox and State of Tennessee, have invented a new and useful Improvement in Sewing-Machines, of which the following is a specification, reference being had to the accompanying drawing.

10 My improvement relates particularly to machines for sewing material which is in the form of rope-like masses.

The chief object of the particular form in which my invention is shown embodied in the accompanying drawings is to sew transversely through a rope-like mass of parallel cords at intervals, the stitches extending through said mass at different angles perpendicular to the length of said mass, so 20 that in the planes of such sewing the cords of which such rope-like mass is composed will be firmly joined to each other and will so remain after said cords have been cut transversely between such sewing planes, to 25 form upholstering tufts, lamp wicks, and other similar articles. But the machine is adapted to other forms of sewing, with or without variation of the mechanism. In the preferred form for the particular work 30 now at hand, such material is moved longitudinally through the machine and is also at intervals partially rotated with reference to its line of longitudinal movement, such rotation taking place step-by-step between 35 the needle movements until the sewing in a given transverse plane in the rope-like mass has been completed, and the entire mass being then given a longitudinal movement equal to the distance between two sewing 40 planes.

This improvement is a modification of the mechanism made the subject matter of my application Ser. No. 511,394, filed August 5, 1909, for Letters Patent, renewed December 45 26, 1912, Serial No. 738,754, for an improvement in sewing machines.

In the accompanying drawings, Figure 1 is a front elevation of a machine embodying my improvement; Fig. 2 is a section on the line, 2—2, of Fig. 1 looking downward; Fig. 3 is a longitudinal upright section through the guide tube and fixed rope guide shown in Figs. 2 and 4; Fig. 4 is an upright section on the line, 4—4, of Fig. 2 looking toward the right, the needle bar driving shaft and connections between the latter and the

mechanism of Fig. 2 being added; Fig. 5 is a front detail elevation of the mechanism shown in Fig. 4, the portion of the guide tube shown being without a bearing; Fig. 6 is a section on the line, 6—6, of Fig. 1 looking toward the left; Fig. 7 is a section on the line, 7—7, of Fig. 1, looking toward the right; Fig. 8 is a transverse upright section through the rope looking toward the discharge end of the guide tube.

For convenience in description, the line in which the needle reciprocates is herein termed the "needle path," and the rope-like mass upon which the sewing is done is herein termed the "rope," while the places on said rope to which the sewing is done are termed the "sewing stations" or "sewing planes." These stations or planes are to be separated from each other more or less according to the articles to be made by the transverse severing of the rope after it has been sewed.

Referring to said drawings, A is an ordinary sewing head comprising the usual arm, 80 B, and the usual base plate, C. Said base plate has feet, D, resting upon a foundation plate, F, and one or more bolts, E, rise from said foundation plate, F, through said base plate and serve to bind said sewing head to 85 said foundation plate.

Extending through the arm, B, of the sewing head, A, is the usual horizontal, rotary needle bar shaft, 1, for driving the upright reciprocating needle bar, 2, which bears at 90 its lower end the needle, 3. The shaft, 1, is surrounded by a loose gear wheel, 4, adjacent which is a clutch, 5, rotating with said shaft and adapted to engage said gear wheel. Said gear wheel is rotated by a larger spur gear wheel, 6, which is rigid on a horizontal driving shaft, 7, resting in bearings, 8 and 9. Said shaft serves as a constantly-moving main driving member. On the outer end of said driving shaft are a fixed pulley, 10, 100 and a loose pulley, 11. By means of a belt applied to said fixed pulley, the latter is rotated clock-wise as viewed from the right in Fig. 1, whereby contra-clockwise movement is imparted to the gear wheel, 4, as viewed 105 from the same direction. When said clutch is closed the shaft, 1, rotates in the same direction. For the details of said gearing, reference is made to my above-mentioned application. The needle, the needle bar, and 110 the needle bar driving shaft receive motion periodically from the main driving member

and are to be regarded as a portion of the stitching mechanism.

Adjacent the needle, 3, is the usual presser foot, 12, and beneath the needle and below the base plate, C, is a shuttle. The shuttle, 5 needle, needle bar, and the parts directly associated therewith may be of any well known form, and I therefore deem it unnecessary to illustrate and describe the same in detail. 10 And, if so desired, the stitching mechanism may be of the chain-stitch form, omitting the shuttle.

In lieu of the ordinary reciprocatory feed dog or plate located below and acting in conjunction with the yielding presser foot, 12, for feeding the sheet-form cloth or other material horizontally across the base plate, I use a horizontal guide tube, 13, one end of 15 which is adjacent the needle, and a fixed rope guide, 14, set axially in line with said tube at the opposite side of the needle, and a pair of opposing and constantly-rotating but intermittently-gripping feed rollers, 80 and 81, between which the axial line of said tube 20 and said fixed guide, 14, passes. Said gripping rollers are normally forced together sufficiently to make engagement with the rope lying between them, and when the rope is to be held stationary, said rollers are forced from each other sufficiently to release the rope, as will be hereinafter described. And by mechanism to be hereinafter described, the guide tube, 13, is slightly rotated between strokes of the needle until said tube 25 has been given approximately one-half of a rotation, so that stitches are taken transversely through the rope in the same plane at various angles. The means by which this rotation is effected will be hereinafter described. And it may be here stated that said tube is rotated in one direction after sewing in one plane or at one station on the rope and is rotated in the reverse direction while sewing in the next plane or at the next station, 30 whereby the twist (a little more than one-half of a turn) given to the rope during the sewing at one station is undone during the sewing at the next station. And the needle line is a little at one side of the axis of said tube so that the needle will penetrate the rope a little at one side of the rope axis and the stitches will cross each other at diverse points in the sewing plane. (See Fig. 12.) 35 In other words, the needle line is between the axis and the perimeter of the longitudinally extended space inclosed by the tubular guide, 13, so that the needle will, during each reciprocation, penetrate the rope issuing from said tubular guide at one side of the axis of the rope; or the path of the rope crosses the stitching line with the axis of the path at one side of said line.

At the rear of the sewing head and parallel to the length thereof, and a little above the base plate, C, is a horizontal line shaft,

16, having its ends in fixed bearings, 17. Said line shaft receives rotation from the drive shaft by means of the gear wheels, 18 and 19, as described in my above-mentioned application, such rotation being continuous with the driving shaft, but at a slower speed. 70

The guide tube, 13, rests in a long horizontal bearing, 34, secured on the base plate, C, by means of screws, 35. Oil holes, 36, are 75 formed in said bearing. The end of said tube which is the farther from the needle is expanded to form an annular head, 37, and the space within the tube is made flaring or funnel-form in said head. Between said head and the bearing, 34, and resting against the latter, a collar, 38, surrounds the tube and is immovably fixed thereto. Between said collar and said head are six equi-distant horizontal rods or teeth, 39, to be engaged by pawls for the partial rotation of said tube. The ends of said rods extend into cavities, 40, in the collar, 38, and into cavities, 41, in the head, 37. Said collar holds the tube from movement toward the needle, 80 and the opposite end of the tube being of no larger diameter than the bearing, the tube is held against movement through the bearing away from the needle by means of a hook-form bracket, 42, secured to the bearing, 34, by means of a screw, 43, and reaching across a portion of the free end face of said collar so as to hold the latter against movement away from said bearing, which, 85 obviously prevents the tube from moving in 90 the same direction.

An arched standard, 44, has legs, 45, rising from opposite sides of the head, 37. On the upper end of said standard, is a forward extension, 46, in which is an upright guide 105 way, 47, in which rests an upright reciprocatory bar, 48, having at its upper end an anti-friction roller, 49, bearing against a cam, 20, on the horizontal rotary needle bar driving shaft, 1. The lower end of said bar, 48, is forked and a pintle, 21, extends through the fork end and projects forward therefrom. A contracting coiled spring, 22, is attached, by its lower end, to the projecting end of said pintle and by its upper end to a horizontal stud, 23, supported rigidly on the standard, 44, at a suitable distance above the pintle, 21. Said spring constantly draws upward on the bar, 48, and lifts the latter as far as permitted by the cam, 20. 110 During each rotation of the needle bar driving shaft, 1, the cam, 20, forces said bar, 48, downward. Since the needle bar reciprocates once during each rotation of the shaft, 1, it follows that there is one reciprocation 115 of the bar, 48, for each reciprocation of the needle bar and needle. But the cam, 20, is so placed upon the shaft, 1, as to cause the bar, 48, to move downward while the needle bar moves upward, in order that the work 120

to be done by said bar, 48, may be done while the needle is raised out of the rope which is being sewed.

In the forked end of the bar, 48, the upper ends of two pawls, 50, are hinged on the pintle, 21, one of said pawls extending to one side and the other to the other side of the toothed wheel formed by the collar, 38, head, 37, and teeth, 39. Said pawls are adapted to engage the teeth, 39, for pressure against the latter when the bar, 48, is moved downward. Each of said pawls has at its lower end a recess, 51, adapted to receive one of the teeth. A C-shape spring, 52, engages said pawls by its ends so as to draw said pawls toward each other and toward the tube, 13, and the teeth, 39. But said pawls are alternately held out of engagement with said teeth by means of the horizontal shifting bar, 53. Said bar is supported slidably in ways, 54, opposite the end of a shaft, 55, and a cam, 56, which is rigid on said shaft. Said shaft has a bearing in a standard, 55^a, and surrounding said shaft is a spur gear wheel, 57, rigid on said shaft and meshing with a smaller spur gear wheel, 58, on the line shaft, 16. Through said gear wheels, 58 and 57, constant rotation is imparted to the cam, 56, from said line shaft. On the bar, 53, anti-friction rollers, 59, extend into the path of said cam, said rollers being located at opposite sides of said cam and near enough to the latter to cause substantially constant engagement between said rollers and said cam. Thus said bar is reciprocated lengthwise, much the same as the needle bar is reciprocated; but said cam has a concentric or dwell portion, 56^a, covering a sufficient arc to cause said bar to remain stationary during the time the needle bar and needle are reciprocated. And it will be observed that the pawls, 50, reciprocate during the periods of rotation of the needle bar; for the needle bar and said pawls both receive motion from the needle bar drive shaft, 1, the latter rotating when the clutch, 5, engages the spur gear, 4, on the shaft, 1. But during such periods of reciprocation of said pawls and the needle bar, said pawls and said bar must reciprocate alternately; that is to say, when the needle bar rises from the rope, the pawls are pushed downward, one engaging a tooth, 39, and partially turning the guide tube while the needle is free from the rope. And when the needle bar and needle again descend, the pawls rise leaving said tube and the rope stationary. On the bar, 53, and between the pawls, 50, are two stops, 60, one adapted to bear against the right-hand pawl, 50, and the other adapted to bear against the left-hand pawl, 50. The position of said stops is such as to hold the right-hand pawl away from the teeth, 39, when the bar, 53, is in its right-hand position and to hold the left-hand

pawl away from said teeth when said bar is in its left-hand position. Thus, while said pawls are reciprocated in unison by the reciprocatory shaft, 48, only one of said pawls operates at any time, and the direction of rotation of the guide tube, 13, is changed when the engagement of said pawls is reversed. The intervals between these reversals is determined by the relation of the gears, 57 and 58. The tube, 13, is preferably given a little more than a half turn between such reversals.

On the bar, 53, are two additional pawls, 62, one being adjacent to one of the pawls, 50, and the other adjacent to the other pawl, 50. The function of these pawls is to so engage the teeth, 39, as to prevent reversal of the guide tube while the adjacent pawl, 50, is being retracted after it has made a forward movement. A C-shape spring, 64, engages the pawls, 62, with its ends and tends to press said pawls toward each other and into the path of the teeth. But the movement of each of said pawls toward the other is limited by a stop, 65, set upon the bar, 53, in position to meet a shoulder, 66, on the adjacent pawl, 62, and the relative arrangement of the parts is such as to permit each of said pawls to turn far enough only to engage the teeth, 39, when the adjacent pawl, 50, is permitted to engage said teeth.

For feeding the rope forward longitudinally through the guide tube, 13, periodically to bring new sewing planes or stations to the needle, a pair of horizontal superposed gripping rollers, 80 and 81, are placed at opposite sides of and transversely to the axial line of the guide tube, 13, and the rope is made to pass between said rollers. Said rollers are supported in two columns, 82, the shaft, 83, of the roller, 80, having bearings in said columns, while the shaft, 84, of the upper roller, 81, has bearings in a yoke, 85, movable up and down in upright slots, 86. The shaft, 83, takes power from the line shaft, 16, through spiral gears, 87 and 88. And the upper roller, 81, receives power from the lower roller, 80, through a spur gear, 89, on the shaft, 83, meshing with the spur gear, 90, on the shaft, 84. Since the line shaft, 16, rotates constantly, these feed rollers, 80 and 81, will rotate constantly. But they will feed the rope forward only when the upper roller, 81, is pressed downward sufficiently to cause the firm gripping of the rope between said rollers. The roller, 81, is pressed downward by pressing the yoke, 85, downward. This is accomplished by means of an upright expanding coiled spring, 91, having its lower end resting upon said yoke and having its upper end bearing against a bridge, 92. When the rope is not to be fed forward, the effect of said spring must be overcome and the yoke, 85, raised. For this purpose, an upright link, 93, is

coupled by its lower end to the yoke and by its upper end to an arm, 94, on a rock shaft, 95, resting in a bearing, 96, supported by a bracket 97, extending laterally from the 5 columns, 82, to a point above the line shaft, 16. On the rock shaft, 95, is an arm, 98, extending downward between the shaft, 16, and the columns, 82, into the path of a cam member, 99, on the line shaft, 16, which has 10 a cam face, 100, on a portion of its circumference adapted to press said arm laterally so as to cause the turning of the rock shaft, 95, for lifting the arm, 94, link, 93, and yoke, 85. Said cam face, 100, is so placed 15 radially upon the line shaft, 16, and is of such length as to cause the lifting of said yoke and the feed roller, 81, during the operation of the needle.

I claim as my invention:

20 1. In a sewing machine, the combination with a stitching mechanism comprising a needle, of a constantly-moving main driving member in operative relation with the stitching mechanism for periodically imparting motion to said mechanism, mechanism for moving a rope lengthwise across the needle path, means for transmitting motion from said main driving member to said rope-moving mechanism, and mechanism in operative relation with the stitching mechanism for partially rotating said rope between 25 stitches, substantially as described.

2. In a sewing machine, the combination with a stitching mechanism comprising a 30 needle and a needle bar and a rotary needle bar shaft, of a constantly-moving main driving member in operative relation with said needle bar shaft for periodically imparting motion to said shaft, mechanism for moving a rope lengthwise across the needle path, means for transmitting motion from said 35 main driving member to said rope-moving member, and mechanism in operative relation with said needle bar shaft for partially rotating said rope between stitches, substantially as described.

3. In a sewing machine, the combination with a stitching mechanism comprising a 40 needle and a needle bar and a rotary needle bar shaft, of a constantly-moving main driving member in operative relation with said needle bar shaft for periodically imparting motion to said shaft, mechanism for moving a rope lengthwise across the needle path, 45 means for transmitting motion from said main driving member to said rope moving member, and mechanism in operative relation with said needle bar shaft for partially rotating said rope between stitches, such 50 rotation being in one direction during one period and in the other direction during another period, substantially as described.

4. In a sewing machine, the combination with a stitching mechanism comprising a

needle, of a constantly-moving main driving member in operative relation with said stitching mechanism for periodically imparting motion to said mechanism, mechanism for moving a rope lengthwise across the needle path, a line shaft for transmitting motion from said main driving member to said rope moving mechanism, and mechanism in operative relation with the stitching mechanism for partially rotating said rope between stitches, substantially as 55 described.

5. In a sewing machine, the combination with a stitching mechanism comprising a 60 needle, of a constantly-moving main driving member in operative relation with said stitching mechanism for periodically imparting motion to said mechanism, mechanism for moving a rope lengthwise across the needle path, a line shaft for transmitting motion from said main driving member 65 to said rope moving mechanism, and mechanism in operative relation with the stitching mechanism for partially rotating said rope between stitches, such rotation being in one direction during one period and in 70 the other direction during another period, substantially as described.

6. In a sewing machine, the combination with a stitching mechanism comprising a 75 needle, of a constantly-moving main driving member in operative relation with said stitching mechanism for periodically imparting motion to said mechanism, mechanism in operative relation with the stitching mechanism for partially rotating a rope 80 between stitches, and other means in operative relation with said main driving member for moving the rope in another direction while the stitching mechanism is out of action, substantially as described.

7. In a sewing machine, the combination with a stitching mechanism, of a constantly moving main driving member in operative relation with said stitching mechanism for periodically imparting motion thereto, 85 mechanism in operative relation with said stitching mechanism for moving the material in one direction between stitches, and other means in operative relation with said main driving member for moving the material at an angle to the direction of movement between stitches while the stitching mechanism is out of action, substantially as 90 described.

8. In a sewing machine, the combination with a stitching mechanism comprising a 95 needle, of a constantly-moving main driving member in operative relation with said stitching mechanism for periodically imparting motion to said mechanism, a tubular 100 guide adjacent the needle, means in operative relation with said stitching mechanism for partially rotating said tubular 105

guide between stitches, and mechanism in operative relation with said main driving member for periodically drawing a rope lengthwise through said tubular guide, substantially as described.

9. In a sewing machine, the combination with a stitching mechanism comprising a needle, of a constantly-moving main driving member in operative relation with said stitching mechanism for periodically imparting motion to said mechanism, a tubular guide adjacent the needle, means in operative relation with said stitching mechanism for partially rotating said tubular guide between stitches, such rotating being in one direction during one period and in the other direction during another period, and mechanism in operative relation with said main driving member for periodically drawing a rope lengthwise through said tubular guide, substantially as described.

10. In a sewing machine, the combination with a stitching mechanism comprising a needle, a needle bar and a needle bar driving shaft, of a constantly-moving main driving member in operative relation with said needle bar driving shaft for periodically imparting motion to said mechanism, a tubular guide adjacent the needle, and means in operative relation with said needle bar driving shaft for partially rotating said tubular guide between stitches, such rotating being in one direction during one period and in the other direction during another period, and mechanism in operative relation with said main driving member for periodically drawing a rope lengthwise through said tubular guide, substantially as described.

11. In a sewing machine, the combination with a stitching mechanism comprising a needle, of a constantly-moving main driving member in operative relation with said stitching mechanism for periodically imparting motion to said mechanism, a tubular guide adjacent the needle, means in operative relation with said stitching mechanism for partially rotating said tubular guide between stitches, and mechanism in operative relation with said main driving member for periodically drawing a rope lengthwise through said tubular guide, said rotating means and said drawing means acting alternately, substantially as described.

12. In a sewing machine, the combination with a stitching mechanism comprising a needle, of a constantly-moving main driving member in operative relation with said stitching mechanism for periodically imparting motion to said mechanism, a tubular guide adjacent the needle, means in operative relation with said stitching mechanism for partially rotating said tubular guide between stitches, such rotating being

in one direction during one period and in 65 the other direction during another period, and mechanism in operative relation with said main driving member for periodically drawing a rope lengthwise through said tubular guide, substantially as described. 70

13. In a sewing machine, the combination with a stitching mechanism comprising a needle and a needle bar and a needle bar driving shaft, of a constantly-moving main driving member in operative relation with 75 said needle bar driving shaft for periodically imparting motion to said shaft, a tubular guide adjacent the needle, means in operative relation with said needle bar driving shaft for partially rotating said 80 tubular guide between stitches, said rotating means and said drawing means acting alternately, substantially as described.

14. In a sewing machine, the combination with a stitching mechanism comprising 85 a needle and a needle bar and a needle bar driving shaft, of a constantly-moving main driving member in operative relation with said needle bar driving shaft for periodically imparting motion to said shaft, a 90 tubular guide adjacent the needle, and means in operative relation with said needle bar driving shaft for partially rotating said tubular guide between stitches, such rotating being in one direction during one period 95 and in another direction during another period, and mechanism in operative relation with said main driving member for periodically drawing the rope lengthwise through said tubular guide, said rotating means and 100 said drawing means acting alternately, substantially as described.

15. In a sewing machine, the combination with the stitching mechanism comprising a needle and a needle bar and a needle 105 bar driving shaft, of a cam on said shaft, means for supporting and guiding a rope, and means in operative relation with said cam for partially rotating said rope supporting and guiding means, substantially as 110 described.

16. In a sewing machine, the combination with the stitching mechanism comprising a needle and a needle bar and a needle bar driving shaft, of a cam on said shaft, 115 means for supporting and guiding a rope, and means in operative relation with said cam for partially rotating said rope supporting and guiding means, such rotation being in one direction during one period 120 and in another direction during another period, substantially as described.

17. In a sewing machine, the combination with the stitching mechanism comprising a needle and a needle bar and a needle 125 bar driving shaft, of a cam on said shaft, automatic means for moving a rope lengthwise through the needle path, means in op-

- erative relation with said cam for partially rotating the rope between stitches, substantially as described.
18. In a sewing machine, the combination with the stitching mechanism comprising a needle and a needle bar and a needle bar driving shaft, of a cam on said shaft, automatic means for moving a rope lengthwise through the needle path, means in operative relation with said cam for partially rotating the rope between stitches, such rotation being in one direction during one period and in the other direction during another period, substantially as described.
19. In a sewing machine, the combination with a stitching mechanism comprising a needle and a needle bar and a rotary needle bar shaft, of a cam on said shaft, a tubular guide, and mechanism in operative relation with said cam for partially rotating said guide between stitches, substantially as described.
20. In a sewing machine, the combination with a stitching mechanism comprising a needle and a needle bar and a rotary needle bar shaft, of a constantly-moving main driving member in operative relation with said needle bar shaft for periodically imparting motion to said shaft, mechanism in operative relation with said main driving member for moving a rope lengthwise across the needle path, means for transmitting motion from said main driving member to said rope moving member, a cam on said needle bar shaft, and mechanism in operative relation with said cam for partially rotating said rope between stitches, substantially as described.
21. In a sewing machine, the combination with a stitching mechanism comprising a needle and a needle bar and a rotary needle bar shaft, of a constantly-moving main driving member in operative relation with said needle bar shaft for periodically imparting motion to said shaft, mechanism in operative relation with said main driving member for moving a rope lengthwise across the needle path, means for transmitting motion from said main driving member to said rope-moving member, a cam on said needle bar shaft, and mechanism in operative relation with said cam for partially rotating said rope between stitches, substantially as described.
22. In a sewing machine, the combination with a stitching mechanism comprising a needle and a needle bar and a needle bar driving shaft, of a constantly-moving main driving member in operative relation with said needle bar driving shaft for periodically imparting motion thereto, a cam on said needle bar driving shaft, mechanism in operative relation with said cam for moving the material in one direction between stitches, and other means in operative relation with said main driving member for moving the material in another direction while the needle bar driving shaft is at rest, substantially as described.
23. In a sewing machine, the combination with a stitching mechanism comprising a needle, of a constantly-moving main driving member in operative relation with said stitching mechanism for automatically periodically imparting motion to said mechanism, of means for supporting and guiding a rope, pawl mechanism in operative relation with said stitching mechanism and with said guiding and supporting means for automatically imparting step-by-step rotation to said supporting means, and automatic means for periodically changing the engagement between said pawl mechanism and said supporting means, whereby the rotation of said supporting means is in one direction during one period and in the opposite direction during another period, substantially as described.
24. In a sewing machine, the combination with a stitching mechanism comprising a needle, of a constantly-moving main driving member in operative relation with said stitching mechanism for automatically periodically imparting motion to said mechanism, a line shaft constantly driven by said driving member, a rotatable member for supporting and guiding a rope, mechanism in operative relation with said stitching mechanism and said rotatable member for imparting step-by-step rotation thereto, and means in operative relation with said line shaft for periodically reversing the direction of said step-by-step mechanism upon said rotatable member, substantially as described.
25. In a sewing machine, the combination with the stitching mechanism comprising a needle and a needle bar and a needle bar driving shaft, of a line shaft, a rotatable member for supporting and guiding a rope, pawls for engaging opposite sides of said rotatable member, means operatively connecting said pawls with said needle bar driving shaft for imparting reciprocatory motion to said pawls, and means in operative relation with said line shaft for alternating the engagement between said pawls and said rotatable supporting and guiding member, substantially as described.
26. In a sewing machine, the combination with a stitching mechanism comprising a needle, of a constantly-moving main driving member in operative relation with said stitching mechanism for automatically periodically imparting motion to said mechanism, of a rotatable member for guiding and supporting a rope, reciprocable means for imparting partial rotation to said guiding and supporting member, such reciprocable means being in operative relation with

said stitching mechanism to receive movement in one direction, and a spring for imparting motion to said reciprocable means in the opposite direction, and means in operative relation with said main driving member for alternating the engagement between said reciprocatory means and said rotatable member, substantially as described.

Copies of this patent may be obtained for five cents each, by addressing the "Commissioner of Patents, Washington, D. C."

In testimony whereof I have signed my name, in presence of two witnesses, this 16th day of November, in the year one thousand nine hundred and eleven.

ERNEST KOELLA.
